F. KUSTER,
ANTIGLARE APPLIANCE,
APPLICATION FILED JULY 29, 1919.

1,360,303.

Patented Nov. 30, 1920.

By his Attorney

William F. Nickel

UNITED STATES PATENT OFFICE.

FREDERICK KUSTER, OF NEW YORK, N. Y.

ANTIGLARE APPLIANCE.

1,360,303.

Specification of Letters Patent. Patented Nov. 30, 1920.

Application filed July 29, 1919. Serial No. 314,153.

To all whom it may concern:

Be it known that I, FREDERICK KUSTER, a citizen of the United States, residing in New York, in the county of New York and State of New York, have invented certain new and useful Improvements in Antiglare Appliances, of which the following is a specification.

My invention relates to an improved anti-glare appliance for the head-lights of moving vehicles, and is adapted to control the illuminating effect which a head-light is designed to afford.

As is well known, modern automobiles, for instance, are frequently equipped with lamps which are of such high power and which disperse their rays in such a manner that chauffeurs driving at night are often temporarily blinded; and great risk of accident, often resulting in serious injury to both automobiles and their occupants, is created. This risk arises from the fact that such lamps throw the light not only downward upon the surface of the road but also upward; and when two machines approach each other in the dark, if either machine carries such strong lights, the glare thereof is thrown directly into the face of the driver of the other; and deprives him for the time being of the ability to see anything immediately ahead of him.

An object of my invention is to provide means for controlling the illuminating effect of head-lights on automobiles and other vehicles by directing the bright glare downward against the road-bed as far in advance of the machine as is necessary, and without diminishing the intensity of the light to any material extent; thereby avoiding interference with traffic and enabling such vehicles to pass each other in the night with perfect safety.

A further object of my invention is to provide means for controlling the illuminating effect of head-lights by an appliance which can be attached to an illuminating device on an automobile or the like so as to give the desired result, without in any way disturbing the operation of the light or entailing any change in its construction.

These and other objects and advantages of my invention will more fully appear from the following specification, taken in connection with the accompanying drawings; which show the best form of my invention now known to me; and the char-

acteristics of my invention are precisely defined in the appended claims. This disclosure, however, is illustrative only, and I reserve the right to resort to changes, not shown herein, but falling within the scope and spirit of my invention, as the same is indicated by the general meanings of the terms and variations of phrase in which the claims are expressed.

65 On the drawings:

Figure 1 is a front elevation of an anti-glare appliance according to my invention.

Fig. 2 is a section on the line 2—2, Fig. 1.

Fig. 3 is a view partly in section showing how my invention can be mounted upon an ordinary automobile lamp.

Fig. 4 is a similar diagrammatic view showing the mode of operation of the anti-glare appliance illustrated in Figs. 1, 2 and 3, as seen from the side of the same; and

Fig. 5 is another diagrammatic view showing how an anti-glare appliance according to my invention permits the light rays from a head-lamp to spread out horizontally.

The same numerals identify the same parts throughout.

In the particular description of the drawings, I refer first to Figs. 1, 2 and 3, whereon the numeral 1 indicates a plate or disk of such shape that it can be substituted for the lens or glass face plate usually employed to close the casings of the lamps carried at the front of an automobile. In this plate or

disk 1, I make an opening 2, shown as being semicircular in shape, and located in the upper half of the plate 1 when the latter is in proper position. To the straight edge of

this opening 2 I affix a shelf or ledge 3 and in the opening I mount a plurality of semicircular projector elements 4. These elements 4 are in greater or less number, as required, and they are spaced equidistantly apart, as indicated in Figs. 1 and 2. Each

of the elements 4 is simply a curved strip having its ends secured to the ledge 3 and parallel to the curved edge of the opening 2; the elements all being concentric with respect to each other and the center of the

plate 1. The outermost element 4 is secured not only to the shelf 3 but also to the curved edge of the opening 2 in the plate, while the others are held by their opposite edges only to the shelf 3, as illustrated particularly in

Fig. 2. The elements 4 are conical, preferably such that their surfaces if prolonged

would meet in a common point directly in front of the middle of the plate 1.

To attach this appliance to a head-lamp of an automobile, the lens or glass plate 5 which generally closes the front of the lamp casing is removed and the appliance is mounted on the lamp in place of it. The appliance acts to cut off the light of the lower half of the lamp and direct the glare 10 from the upper half downward upon the road-bed, ahead of the machine; thereby preventing any strong rays of light from being emitted in an upward direction to dazzle the eyes of persons in a car approaching 15 the automobile bearing the lamp.

The utility and merit of my invention will appear clearly from consideration of the diagrammatic views shown in Figs. 4 and 5.

The elements 4 are arranged at such an 20 angle that they are parallel to the rays of light emitted by the upper half of the illuminating member 6 after they are thrown forward by the reflector 5. The plate 1 cuts off the rays from the lower half of the lamp 25 entirely, but the rays from the upper half of the lamp pass through the spaces between the elements 4, are brought to the focus 7; and then illuminate the road 8 ahead; but 30 none of them can pass directly upward and therefore when one machine meets another, the two can pass in safety. The strong rays 35 are prevented from flashing into the eyes of the occupants of the other machine because each lamp can be shaded both by the elements 4 and the lower half of the plate 1. At the same time the rays of the light from the lamp can be diffused horizontally to the same extent as if an ordinary lamp or lens were employed. See Fig. 5.

40 Of course each head lamp of an automobile can be equipped with my appliance so that the upward glare from both sides of the car can be eliminated completely.

Fig. 3 shows how an anti-glare appliance 45 can be attached to an ordinary head-lamp in place of the glass which is used on same. I merely take off the glass and put on the plate 1 with the elements 4 in its stead; and then secure the anti-glare appliance against 50 displacement by means of the ring 9. This ring may engage the casing of the lamp by means of a bayonet joint or be secured in any other way, and it will be apparent that 55 my appliance can be attached to a lamp of any construction merely by taking off the glass and putting the appliance in the place of same. The lenses or glass face plates of such lamps may be affixed in various ways; but in Fig. 3, the casing 10 is shown as having 60 a ring 9, which fits over the open end of the casing against a rib 11. This ring 9 has an inturned edge 12 which retains the glass against the rim of the casing 10. I may use the appliance alone or with a dished glass 65 cover 13, having a rim 14. This cover fits

over the front of the appliance, and the two may be held on together by the ring 9. If desired, the appliance and the cover may be fastened to the retaining ring, to be handled therewith as a single unit.

70

The elements 4 and plate 1 are preferably metal or other suitable material, and the convex surfaces of the elements 4 should not be polished, but should be of dull finish.

To secure the elements 4 in the opening 2, 75 they may be soldered to the ledge 3, or have projections on their ends to pass through slots in the shelf 3 and be bent over against the bottom of the shelf 3.

From this description it will be apparent 80 that my invention is simple and can be employed on any automobile, truck, locomotive, or other vehicle, without necessitating any change in the structure of the lamps with which the vehicle may be equipped. It does 85 not reduce the intensity of the light emitted by the lamp, but merely regulates the direction of the light so as to obviate the glare which would usually be thrown into the eyes of occupants of approaching vehicles; while 90 at the same time it gives the road-bed as much illumination as an ordinary lamp can give.

The space between the ledge 3 and the smallest element 4 is closed at 15, to screen 95 the filament of the bulb 6, which has its center at the level of the shelf 3.

The elements 4 should each be arranged at such an angle that the front or outer edge of each, shown at the left in Fig. 2, 100 is closer to the center of the front edge of the shelf 3 than the inner or rear edge of the one immediately below it is spaced from the center of the rear edge of this shelf, which should be horizontal when the appliance is in position. Such a construction 105 is indicated in Figs. 2 and 4, and insures the prevention of any of the intensely brilliant rays of light from passing through the appliance except downward. At the 110 same time, the convex surfaces of these elements being of dull finish, without being polished, as has been stated, some of the light may strike the concave or lower faces of these elements and be thrown against the 115 convex or upper faces of the adjacent ones and thus be thrown outward and upward to enable the lamp to be seen by one in line with it. These rays, however, are comparatively weak and have not the strong glare 120 that would blind a chauffeur. In other words, any light reflected forward and perhaps upward from the convex faces of the elements 4 serves merely to enable anyone 125 who approaches the lamp or who may be approached by an automobile carrying it to perceive the position of the lamp and thus be informed that a car is approaching; although his eyes may be above the level of the rays which pass through the focus 7, Fig. 4, 130

and are directed downward against the road-bed. These comparatively weak rays are shown in Fig. 4 by the line 16 passing above the focus 7. If some of the light emitted by the lamp were not allowed to be thrown forward and upward in this way the occupants of an approaching machine could not see a lamp equipped with my anti-glare appliance at all; but with the construction described, enough light is reflected upward to serve to apprise a beholder that a car is approaching; while all of the strong rays and the dangerous glare of the lamp are directed downward and prevented from passing upward, as already set forth.

The forward edge of each element 4 must be closer to the middle of the front edge of the shelf 3 than the rear edge of the next lower element is to the middle of the rear edge of the shelf because otherwise an observer in line with the lamp could receive some of the strong rays from the reflector 5 passing through between the elements 4 and directly upward and outward. Thus all the upward glare would not be eliminated and the eyes of the driver of an approaching car would not be properly shielded.

The elements 4 may be arranged at dif-

ferent angles or all at the same angle; provided that the forward edge of each is closer to the middle of the front edge of the shelf 3, than the rear edge of the next lower is to the middle of rear edge of the shelf 3.

Having described my invention, what I believe to be new and desire to protect by Letters Patent of the United States is:—

1. An anti-glare appliance comprising a plate having a semi-circular opening in one half of same, a shelf attached to the straight edge of said opening, and a plurality of semi-circular, conical projector elements located in said opening having their ends attached to said shelf.

2. An anti-glare appliance comprising a plate having a semi-circular opening in same, a shelf attached to the straight edge of said opening, and a plurality of semi-circular, conical projector elements located in said openings and having their ends attached to said shelf, said elements being concentric and the space between the smallest element and the shelf being closed.

In testimony whereof, I have signed my name to this specification this 26 day of July, 1919.

FREDERICK KUSTER.
